AIR HUMIDIFIER AND CLEANER

Hornby Sewell Baldwin, Perth Amboy, N. J.

Application June 26, 1935, Serial No. 23,551

1 Claim. (Cl. 183—8)

This invention relates to an air humidifier and cleaner.

An object of the invention is to provide a device of this character which subjects air drawn therethrough to the action of flowing water passing over filters or screens through which the air is drawn. The flowing water carries off the dirt and foreign particles into a suitable trap so that the device is self-cleaning and the operation is a continuous one.

A further object is to provide an apparatus of this character which is especially designed for humidifying and cleaning air passing to a carburetor and which utilizes hot water from the cooling system of the motor and causes the water after its action in the apparatus to return to the system after the dirt and foreign particles have been deposited into a trap.

A further object is to provide an apparatus of this character which compels the air passing through the same to pass through a series of screens which may vary in their texture and which are subjected to the action of flowing hot water so that the air not only passes through the screens, but through the flowing water which carries off the dirt and foreign particles sucked into the device with the air and operates not only to humidify the air, but to clean the same as well, and the flow of water keeps clean the screens through which the air passes so that the apparatus is in a very real sense self-cleaning.

With these and other objects in view, the invention consists in certain novel features of construction and combinations and arrangements of parts, all of which will be more fully hereinafter described and pointed out in the claim.

In the accompanying drawing—

Figure 1 is a view more or less diagrammatic illustrating my improved apparatus in operative position relative to an internal combustion engine or motor and its carburetor;

Figure 2 is a view in longitudinal section through my improved humidifier and cleaner;

Figure 3 is a view in transverse section on the line 3—3 of Figure 1.

1 represents an internal combustion engine or motor having the ordinary radiator 2 and circulating pipe 3 and a pump 4 to maintain a circulation of water through the jacket of the engine or motor and through the radiator. Reference character 5 indicates any suitable form of carburetor with which the engine is equipped and at the air inlet end of this carburetor my improved device or apparatus is located and will now be described in detail.

6 represents a casing which is somewhat elongated and which may be cylindrical in form and may comprise separable sections secured together as shown at 7 or may be made in any other way desired. This casing 6 has an air inlet 8 at one end and an air outlet 9 at its other end which may be operatively connected in any desired manner with the inlet 10 of the carburetor 5. 11 represents a water supply pipe which is connected to the engine or motor at a point 10 where the water in the system is hottest as it is desirable to supply this water to my apparatus as hot as possible. The pipe 11 extends along the upper portion of the casing 6 and supplies water to a plurality of disk-like screens 12. 15 These screens 12 may be made of any desired material and they are preferably reinforced and held taut by means of wires 13 or other more or less rigid material at the edges of the disk-like screens. The pipe 11 extends through openings 14 in the upper portions of the screens and water flows from outlets 15 in the pipe over these screens. Some of these outlets may constitute mere orifices as indicated and others may constitute nipples and certain of the screens may constitute a single thickness of material and may be of wire mesh, and this is particularly true of the screens adjacent the inlet ends of the apparatus as these screens will stop larger particles and foreign matter before reaching the finer mesh screens throughout the major portion of the casing. The screens 12 throughout the major portion of the casing constitute two thicknesses of material with the discharge orifices or nozzles 15 of the pipe 11 discharging between them 20 as clearly shown in Figure 2 of the drawing, so that the water escaping from the pipe not only saturates the screens, but flows freely over them, and this water more or less dirty escapes through an outlet 16 at one end of the casing. This outlet 25 communicates with a trap 17 having a removable portion 18 which may be emptied from time to time and the trap 17 is connected to a return pipe 19 connecting the same with the pump 4 so that when the pump is working the 30 circulation is insured through the apparatus. To facilitate the escape of the water, I preferably provide the casing 6 with a tapering gutter 35 at its lower portion communicating at its 40 outlet end with the outlet 16.

The operation of the apparatus is as follows:

Hot water flowing from pipe 11 passes over the screens or filters 12 and the air entering at 45 8 flows through these streams of water so that 50 55

all dirt and foreign matter is removed from the air and is carried off and deposited in the trap 17. The air is humidified by the action of its contact with the hot water and passes to the carburetor clean, humidified, and slightly heated.

5 While I have illustrated and described what I believe to be a preferred embodiment of my invention, it is obvious that various changes might be made in the general form and arrangement 10 of parts without departing from my invention, and hence I do not limit myself to the precise details set forth but consider myself at liberty to make such changes and alterations as fairly

fall within the spirit and scope of the appended claim.

I claim:

An air cleaner and humidifier including an elongated casing, a water pipe extending through 5 the upper portion of the casing, disk-like screens in the casing having openings receiving the pipe, certain of said screens constituting two thicknesses of material, and said pipe having outlets directing water between the thicknesses of ma- 10 terial.

HORNSBY SEWELL BALDWIN.
